COMPRESSED AIR CIRCUIT BREAKER

Haakon Forwald, Valhalla, Sweden, assignor to
 Alimanna Svenska Elektriska Aktiebolaget,
 Västeras, Sweden, a Swedish corporation

Application August 4, 1949, Serial No. 108,522

Claims priority, application Sweden
 August 7, 1948

3 Claims. (Cl. 200—148)

1

In spite of the recent development of electrical circuit breakers it is still very difficult to produce circuit breakers able to carry large currents and interrupt the large short circuit currents now common on the generator side in modern power stations. It is especially difficult to procure circuit breakers able to interrupt the short circuits up to 100 ka, which may occur.

The present invention relates to a circuit breaker, which is able to carry the largest service currents which may occur and also the largest short circuit currents. According to the invention the circuit breaker consists of two or more electrically series-connected breaking gaps, which, however, are connected pneumatically in parallel, the compressed air being delivered to them simultaneously through parallel air delivery pipe lines or channels. The main breaking gaps may, however, be bridged over by parallel contacts, which are electrically connected in parallel, but, with respect to the delivery of the breaking air, are connected in series with the main breaking gaps.

On the accompanying drawing, a number of forms of the invention are shown, where Figs. 1a and 1b show one phase of a multiphase circuit breaker, Fig. 2 shows one phase of a compressed air circuit breaker with two series-connected breaking gaps and a single bridging contact pair connected in parallel with them, and Fig. 3 shows one phase of a compressed air circuit breaker with two series-connected breaking gaps and two parallel-connected bridging contact pairs, which are pneumatically connected in series with the main breaking gaps.

In Figs. 1a and 1b, 1 designates the compressed air container and 2 the air blast valves and 3 a frame work carrying the container 1 and the circuit breaker with its disconnecting switch. The poles of the circuit breaker consist of the main breaking gaps 4, each of which has a movable contact 5 and a sleeve shaped stationary contact 6. The main breaking gaps are enclosed in insulating cylinders 7, which in turn are carried by insulating cylinders 8, which rest on insulating cylinders 9. Between cylinders 8 and 9, however, a metal part 10, is connected with one of the lines 13 of the circuit breaker. The insulating cylinders 9 enclose the movable bridging contacts 11, which are arranged to engage in the stationary bridging contacts 12, which are connected with a strip, to which the disconnecting switch arm 14 is attached. The arm 14 is operated by an operating lever 15, and it engages in the contact 16 attached to the in-

2

sulator 17. The circuit breaker pole itself is carried by an insulator 18 resting on the frame 3. Conductors 19, 20 and 21 are also provided. By means of the conductor 19 the breaking pair at the extreme right is connected with the line 13 and this breaking pair is by means of the conductor 20 joined with the breaking pair in the middle pole, and further the latter breaking pair is by means of the conductor 21 joined with the main breaking gap in the left pole, which latter is joined over the line 22 with the strip 12 and thus with the disconnecting switch arm 14. The bridging contact pairs 11 and 12 are, however, mutually connected in parallel so that their movable contacts are joined with or formed in the part 10, whereas the stationary contacts are joined with or formed in the part 12. The flow of current through the circuit breaker will thus be as indicated on the drawing by the arrows. Instead of arranging a valve for each pole as shown on the drawing, it is of course possible to arrange a valve common for all poles.

In Figs. 2 and 3 similar parts are designated by the same numbers as in Figs. 1a and 1b. In the arrangement shown in Fig. 2 the main breaking pairs 5', 6' are arranged in two parallel cylinders 7', which at the lower end are joined by means of a pipe 23, which in turn is attached to the upper end of the cylinder 8', this cylinder being attached to a metal part 10' resting on the cylinder 9', which cylinder in turn is attached to the strip 12', on which the disconnecting arm 14 is journalled. For the two breaking gaps in each phase a common bridging contact 11' is provided. The whole circuit breaker is carried by the insulator 18'.

The arrangement according to Fig. 3 differs from that of Figs. 1a and 1b only in that in each phase two series-connected breaking pairs 5'', 6'' are arranged, each being pneumatically coupled in series with a parallel contact, which two parallel contacts 11'', 12'' are mutually connected in parallel and connected in parallel with the two breaking gaps. The main breaker pairs 45 are arranged in two parallel cylinders 7'' and are connected by a conductor 20'' attached to the upper end of cylinders 8'' which are attached to the metal part 10'' resting upon the cylinders 9'' which latter are attached to the strip 12'' to which the disconnecting arm 14 is journalled.

I claim as my invention:

1. A compressed air circuit breaker comprising a plurality of pneumatically operated main breaking gaps, means for electrically connecting said gaps with each other in series, at least one

pneumatically operated bridging contact, means connecting said contact electrically in parallel to the whole series of the main breaking gaps, means connecting said main breaking gaps mutually in parallel with respect to the air flow, and means connecting said gaps pneumatically in series with said bridging contact.

2. A compressed air circuit breaker comprising a plurality of main breaker gaps arranged side by side, means connecting said gaps electrically in series with each other, a single bridging contact, means connecting said bridging contact electrically in parallel with said breaker gaps, a passage for the supply of compressed air to said bridging contact, and passages for the supply of air from said bridging contact to said gaps to supply air in parallel to said main gaps from said bridging contact.

3. A compressed air circuit breaker comprising

ing a plurality of main breaker gaps arranged side by side, means electrically connecting said gaps in series with each other, an equal number of bridging contacts, means electrically connecting said bridging contacts in parallel with said breaker gaps, passages for the supply of compressed air to said bridging contacts; and a passage for the supply of air from each of said bridging contacts to one of said breaker gaps to supply air in parallel to said main breaker gaps from said bridging contacts.

HAAKON FORWALD.
